UNITED STATES PATENT OFFICE.

JOSEPH H. MISHLER, FRANK B. STUMPF, AND MICHAEL E. DONAHAY, OF EUREKA, ILLINOIS.

DESIGN FOR A BADGE.

SPECIFICATION forming part of Design No. 26,455, dated December 29, 1896.

Application filed September 2, 1896. Serial No. 604,687. Term of patent 3½ years.

To all whom it may concern:

Be it known that we, JOSEPH H. MISHLER, FRANK B. STUMPF, and MICHAEL E. DONAHAY, citizens of the United States, residing at Eureka, in the county of Woodford and State of Illinois, have invented a certain new and useful Design for a Badge; and we do hereby declare that the following is a full, clear, and exact description of the invention, which will enable others skilled in the art to which it appertains to make and use the same.

This invention relates to a new design for a badge or button, of which the following is a specification, reference being had to the accompanying drawing.

The figure of the drawing represents a horseshoe with a cross located within it and a crown of thorns placed upon the top.

The design consists in a badge having represented thereon certain elements disclosed in the drawing and understood from the following description. The body of the badge is of horseshoe shape, and upon its face near the

outer edge are located sixteen cylindrical panels. Eight of these panels are placed on each side or limb of the shoe, as shown. Within the shoe, as before described, is placed a cross, upon which a suitable word or words or sentence may be placed. At the intersection of the arms of the cross is located a cylindrical panel. Upon the top of the shoe is represented a crown of thorns, upon which any suitable word, words, or sentence may be placed.

This badge is intended more especially for use in political campaigns.

What we claim as new is—

The design for a badge as herein shown and described.

In testimony whereof we affix our signatures in presence of two witnesses.

JOSEPH H. MISHLER.

FRANK B. STUMPF.

MICHAEL E. DONAHAY.
